UNITED STATES PATENT OFFICE.

BENJAMIN BRODIO, OF NEW YORK, N. Y., ASSIGNOR TO THE SUPERHEATER COMPANY, OF NEW YORK, N. Y., A CORPORATION OF DELAWARE.

WATER-TUBE BOILER WITH SUPERHEATER.

1,417,024.

Specification of Letters Patent. Patented May 23, 1922.

Application filed June 4, 1919. Serial No. 301,819.

To all whom it may concern:

Be it known that I, BENJAMIN BRODIO, citizen of the United States, and resident of New York, in the county of New York and State of New York, have invented certain new and useful Improvements in Water-Tube Boilers With Superheaters, of which the following is a specification.

My invention relates to water tube boilers of the type having two downwardly diverging banks of water tubes and has for its purpose the provision of means whereby the superheater may be placed in the upper part of the combustion chamber formed by the two banks of tubes and yet may be protected against an excessive amount of heat from the furnace located directly below this combustion space.

In the accompanying drawings, my invention is illustrated in two forms; Fig. 1 showing a cross section of boiler with my invention in place; Fig. 2 being a longitudinal central section of Fig. 1 and Fig. 3 illustrating a modification.

The boiler to which my invention is shown applied in the drawings will be seen to be composed of a left and a right half which are generally speaking symmetrical with each other; each comprises an upper drum 1^a and 1^b respectively and a lower drum 2^a and 2^b respectively joined to each other by water tubes. These water tubes diverge downwardly so that the lower drums are spaced apart farther than the upper. The water tubes of each half are grouped into three sets numbered 3^a, 4^a, 5^a, 3^b, 4^b and 5^b respectively. Between the two groups of tubes 3^a and 3^b, there is thus defined a combustion space wider at the bottom than at the top. Below this combustion space is located the furnace chamber 6. Gaseous products from this furnace have their combustion completed in the combustion chamber and are then guided over the banks of tubes by means of baffles 7^a, 8^a and 7^b, 8^b respectively to the connections leading to the stack and numbered 9^a and 9^b respectively. The entire structure is enclosed in an appropriate housing.

As far as described, this structure is of ordinary type and not modified in any way for my purpose. Its operation may be briefly stated, as follows: The boiler being filled to the proper level with water, the hot gases from the furnace and combustion

chamber pass upward along the tubes of the banks 3^a and 3^b, then downward through the banks 4^a and 4^b again upward over banks 5^a, 5^b and so out through the connections 9^a and 9^b. In passing over the tubes as described, they heat the water, generating steam, which is collected in the drums 1^a and 1^b and is taken off from them through the steam pipes 10^a and 10^b. Various places have been proposed for locating superheaters in boilers of this general type, among them the upper portion of the combustion space. This latter location has certain advantages but provisions will have to be made to protect the superheater so located against excessively hot gases coming directly from the furnace. The novel means which I propose herein for this purpose will be found to accomplish the purpose of protecting the superheater and to offer few, if any, objectionable features. A drum 11 is placed in a position parallel to the drums 1^a, 1^b, 2^a and 2^b and at a central point in the combustion space some distance from its top. To this drum are connected the tubes 12^a and 12^b whose other ends are joined to the drums 2^a and 2^b respectively. These tubes 12^a and 12^b are given gentle bends or curves to bring their ends into radial direction where they join the drums. Two other sets of tubes 13^a and 13^b join the drums 1^a and 1^b respectively to the drum 11. The greater portions of these tubes 13^a and 13^b follow in general direction the adjacent tubes of the banks 3^a and 3^b but their lower ends are curved away from these banks toward the drum 11^a which they enter radially. In this manner there is set off a space 14 in which I locate my superheater.

The particular construction of the superheater does not strictly speaking form a part of my invention, but the form shown and described in what follows is found to be a very desirable one. Two sets of superheater elements or units are employed, all of the units being of the same shape. The units are made up of pipe of suitable diameter and gauge, bent into a shape utilizing the space 14 to the best advantage. Their upper ends are joined to the headers 15^a and 16^a, 15^b and 16^b respectively. The headers 15^a and 15^b are connected to the pipes 10^a and 10^b.

In the operation of the boiler the hot gases after leaving the furnace 6 pass through be-

tween the tubes of the sets 12^a and 12^b, part of them going directly over the banks 3^a and 3^b and the remaining portion passing through the sets 13^a and 13^b over the superheater in space 14, back again through the sets 13^a and 13^b rejoining the portion of the gases and going with them into the second pass. The passage through the sets of tubes 12^a, 12^b, 13^a and 13^b does not cool the gases below 10 the point where they will still have enough heat left to raise the temperature of the steam circulating through the superheater units to a high point. But the direct radiation from the furnace is effectually cut off 15 from the superheater so its units are not injured even at times when no steam is circulating through them.

The pipes in the sets 12^a, 12^b, 13^a and 13^b as well as the drum 11 are in no danger of 20 being injured by the heat as they are at all times filled with water and function very much like the boiler tubes proper. Any steam that is generated in them is delivered at their upper ends into the drums 1^a and 1^b. 25 Any given unit or element of the superheaters can readily be removed. All that is necessary is to detach its upper ends from the headers after which it can be withdrawn upward through the space between the headers on the left and on the right. During 30 this removal, it will be slid into a space between two units or elements in the set attached to the opposite header.

The means by which the housing is closed 35 at the point 17 is such that it can be removed in convenient sections so that, if it is desired to remove only one or a few units, only enough of this cover has to be removed to make this possible, the remainder remaining 40 intact.

In the variation shown in Fig. 3, the drum 11 is omitted and the tubes 18^a and 18^b run directly from the lower drums to the opposite upward drums. There are shown in 45 this figure two sets, one above the other, of tubes 18^a and 18^b, but it will be understood that at times it will be sufficient to use only one such set from each lower drum to the opposite upward drum. At the point 19, these 50 sets of tubes cross in such manner that the tubes of one set occupy the spaces between those of the other. The other details of this

form do not vary in any manner from that previously described and the function of the apparatus will be evident. It may be pointed out at this place, that in the form of the apparatus of Figs. 1 and 2, there might also be two set of tubes on each side, one above the other.

In practice, there will no doubt occur 60 many variations in my invention without a departure from its spirit.

What I claim is:

1. In a boiler, the combination of two upper and two lower spaced parallel drums, 65 two diverging banks of tubes connecting the two upper to the two lower drums, two additional rows of spaced tubes each communicating with an upper drum and adjacent and parallel to one of the diverging banks 70 for a certain distance from the top and then bent toward and communicating with the opposite lower drum so that the tubes of one cross those of the other and thereby screen the upper portion of the space between the 75 diverging banks from the lower, superheater headers above the upper portion of said space, and tubular superheater elements secured to the headers and looping into said upper portion of the space. 80

2. In a boiler, the combination of an upper and a lower left and an upper and a lower right drum, the lower drums being spaced apart farther than the upper, a left bank of water tubes connecting the left pair of drums, a right bank of water tubes connecting the right pair, a furnace in the lower portion of the space defined by the drums and connecting banks of tubes, a superheater in the upper portion of said space, and means to protect the superheater against direct contact with gases from the furnace comprising a plurality of spaced tubes each comprising a portion placed between the superheater and the furnace and a portion adjacent to and substantially parallel to one of the banks of tubes, and each communicating with an upper drum and the lower drum on the opposite side. 95

Signed at New York in the county of 100 New York and State of New York this 31st day of May A. D. 1919.

BENJAMIN BRODIO.
